US0D1067874S

(12) United States Design Patent (10) Patent No.: US D1,067,874 S
(45) Date of Patent: * Mar. 25, 2025

(54) CHARGING BOX FOR ELECTRONIC CIGARETTE

(71) Applicant: SHENZHEN EIGATE TECHNOLOGY CO., LTD., Shenzhen (CN)

(72) Inventor: Tuanfang Liu, Guangdong (CN)

(73) Assignee: SHENZHEN EIGATE TECHNOLOGY CO., LTD., Shenzhen (CN)

() Term: 15 Years

(21) Appl. No.: 35/518,169

(22) Filed: May 30, 2023

(80) Hague Agreement Data

Int. Filing Date: May 30, 2023

Int. Reg. No.: DM/230894

Int. Reg. Date: May 30, 2023

Int. Reg. Pub. Date: Aug. 25, 2023

(30) Foreign Application Priority Data

Feb. 21, 2023 (CN) 202330064613.1

(51) LOC (15) Cl. 13-02

(52) U.S. Cl.

USPC D13/108

(57) CLAIM

The ornamental design for a charging box for electronic cigarette as shown and described.

DESCRIPTION

1. Charging box for electronic cigarette
2. Charging box for electronic cigarette

1.1 : Perspective

1.2 : Perspective

1.3 : Front

1.4 : Back

1.5 : Left

1.6 : Right

1.7 : Top

1.8 : Bottom

1.9 : Perspective

1.10 : Perspective

2.1 : Perspective

2.2 : Perspective

2.3 : Front

2.4 : Back

2.5 : Left

2.6 : Right

2.7 : Top

2.8 : Bottom

2.9 : Perspective

2.10 : Perspective

Reproductions 1.9 and 2.9 are perspective views, showing a state of use with an electronic cigarette received in the charging box; reproductions 1.10 and 2.10 are perspective views, showing a state of use with an electronic cigarette received in the charging box and an indicator status light. The dot-dash broken lines depict boundaries which form no part of the claimed design. The dashed broken lines and faded portions within dot-dash broken lines depict portions of the of the charging box for electronic cigarette which form no part of the claimed design.

The drawings include surface shading which illustrates contour and not surface ornamentation.

The electronic cigarette and the indicator light are shown for illustrative purposes only and do not form part of the claimed designs.

1 Claim, 14 Drawing Sheets
